UNITED STATES PATENT OFFICE.

FRANK A. AUSTIN, OF SYRACUSE, NEW YORK.

STOP FOR DOOR-HANGERS.

SPECIFICATION forming part of Letters Patent No. 530,818, dated December 11, 1894.

Application filed March 1, 1894. Serial No. 501,933. (No model.)

To all whom it may concern:

Be it known that I, FRANK A. AUSTIN, of Syracuse, in the county of Onondaga, in the State of New York, have invented new and useful Improvements in Stops for Door-Hangers, of which the following, taken in connection with the accompanying drawings, is a full, clear, and exact description.

My invention relates to stops for door-hangers, particularly central stops for sliding or rolling hangers, and the object is to provide a central stop between the hangers of two doors that will serve as a stop for both doors, and that may be tipped or tilted to permit either door to pass by the central stop when desired, as is the case when the rear hangers are to be adjusted.

To this end my invention consists in the combination with a hanger, of a support, and a stop for the hanger mounted on said support and adapted to be moved out of the path of the hanger; and my invention consists also in other combinations hereinafter described and specifically set forth in the claims.

In the drawings forming a part of this specification, Figure 1 is a view of my improved stop, in which view the track is shown in cross-section and an end view of a hanger mounted thereon. Fig. 2 is a front elevation of the track, central brackets and stop mounted thereon, and Fig. 3 is a detached plan view of the complete stop.

Referring specifically to the drawings, A is the frame work around the track, B, and hanger, C, which may be of any well-known form of construction.

D, D are the central brackets supporting the track and forming the support for the movable stop. These brackets are placed a short distance apart, are secured to one side of the frame-work and extend to about the center of the passage in the frame-work where they support the track which lies in grooves therein and is riveted thereto as clearly shown in the drawings in which E is the upper part of the door secured to the hanger. Upon and between the said brackets is mounted the stop, F, which may be cast, but is preferably formed of a piece of sheet-metal.

I do not wish to be limited to the shape of

the stop as it may be greatly varied in form, as is apparent, but my preferred form is shown clearly in the drawings and consists of an inverted U shaped piece, which forms the stop proper, lying below the brackets and in the path of the hanger-frames. Extending from one side of the central part of this piece is a shank or extension F'. This shank is bent upwardly between the brackets and is formed into a flat plate which lies upon the upper side of each of the lower horizontal arms of the said brackets, D, D. The inclined or upper arms of the brackets prevent the stop, F, which, as before mentioned, is loosely held upon the brackets, from being removed. When it is desired to pass either of the doors by this central stop, the stop may be tipped or tilted to the position shown in dotted lines in Fig. 1 by introducing a pencil or short rod through the slot between the jams, and when the door hangers have been adjusted it may be returned to its normal position by the same means.

f, f are rubber bands on the arms of the stop to prevent noise when the hanger-frame comes in contact with the stop. By this form of stop a great deal of time and trouble is saved, allowing the doors to be adjusted without opening the pockets.

I do not desire to be limited to the precise form of track or the brackets or supports for the track or stop as it will be obvious that these parts may also be varied in form without departing from my invention.

Having described my invention, what I claim as new, and desire to secure by Letters Patent, is—

1. The combination with a hanger and a track for the hanger, of a support, and a stop for the hanger mounted loosely on said support and adapted to be moved out of the path of the hanger, as and for the purpose set forth.

2. The combination with a hanger, track and two brackets supporting the track, of a stop in the path of the hanger, and an extension of the stop lying loosely upon and between the said brackets, as and for the purpose described.

3. The combination with the hangers, track and the two central brackets supporting the track, of a central stop in the path of and be-

tween the hangers, an extension of the stop lying loosely upon and between the said brackets, and suitable means to confine the stop to its seat, as set forth.

- 5 4. The combination with the hangers, track and the two central brackets supporting the track, of a central stop in the path of the hangers formed of a single piece of sheet metal, and consisting of an inverted U-shaped
- 10 part, a shank extending from the central part

of the same, and a plate formed on said shank to lie on and between the said hangers, as and for the purpose described.

In testimony whereof I have hereunto signed my name.

FRANK A. AUSTIN. [L. S.]
